UNITED STATES PATENT OFFICE

ALFRED E. SWANSON, OF PALM BEACH, FLORIDA

ARTIFICIAL DENTURE BRUSH

Application filed August 31, 1932. Serial No. 631,242.

This invention relates to an improved artificial denture brush primarily designed for cleaning the teeth and plate of false teeth.

Admittedly, the broad idea of providing a special brush for work of this class is not new. As a matter of fact, I am already familiar with numerous prior patented structures expressly developed for this precise purpose. These devices are of diversified types and depend for distinctiveness on slight structural distinctions.

Comparatively considered, the structure which characterizes the brush of the instant case is fundamentally similar to that of the prior art devices referred to, yet specifically different from a constructional viewpoint to such an extent as to better fulfill the requirements of an accessory of this class.

Manifestly then, the purpose of the present invention is to generally improve upon known prior art and marketed plate brushes by providing one which is simple and economical and capable of expeditious and efficient use in order to accomplish the desired result in an advantageous and reliable manner.

In the drawing:

Figure 1 is a top plan view of a brush constructed in accordance with the principles of the present inventive conception.

Figure 2 is a central vertical sectional and elevational view thereof.

Figure 3 is an edge elevation of the improved brush.

Referring now to the drawing by distinguishing reference characters, it will be observed that the brush per se is distinguished by the numeral 4 and is composed of a multiplicity of appropriate bristles 5 of suitable length attached to a wire frame. The wire frame comprises a core 6 composed of twisted wires of a well-known type whose free end portions 7 are bent laterally at approximate right angles to the axis of the core with their extremities offset inwardly in order to overlie the approximate central portion of the brush.

The core and the brush are substantially horse-shoe shaped in configuration so as to conform to the concavities and irregularities of the denture plate in an obvious manner.

By having the ends of the brush as well as the ends of the wire separated, it is possible to bring the ends toward or from each other to permit the brush to accurately fit dentures of different sizes.

The aforesaid extremities of the twisted wire are brought together in close proximity to form a double shank 7 which is fitted in a socket in the substantially spherical wooden knob or handle 8. The shank may be glued, cemented, or otherwise anchored in place. The numeral 9 merely designates a brass nickel-plated ferrule for finishing and reinforcing purposes.

It is to be noted that the shank and the associated knob 8 is located concentrically over the center of the brush so as to dispose the handle in a convenient position for expeditious manipulation.

In practice, the brush is usable in conjunction with either upper or lower dentures and serves to clean the concavity or retention groove as well as the underside of the plate. Moreover, the bristles are conveniently arranged for cleaning the inner and outer surfaces of the teeth. In using the brush, the knob, which is conveniently shaped, is placed in the palm of the hand and grasped with the fingers so that the brush may be oscillated back and forth in an alternate rotary manner.

This provides an ideal and practical cleaning motion which promotes sanitation and cleanliness and renders the device appreciably different from the aforesaid prior art devices with which I am familiar.

Particularly do I wish to emphasize the horseshoe shaped form of the brush with its end portions as well as the end portions of the wire core spaced apart to permit the diameter of the brush to be regulated as desired. Moreover, I wish to emphasize the offset arrangement of the wire-ends with the extremities brought together to form a shank to which the knob is satisfactorily attached. A brush possessing these characteristics is especially suitable for the work designed and therefore constitutes a novel contribution to the art and trade.

It is thought from the foregoing descrip-

tion that the advantages and novel features of the invention will be readily apparent.

It is to be understood that changes may be made in the construction and in the combination and arrangement of the several parts provided that such changes fall within the scope of the appended claims.

I claim:

1. An artificial denture brush of the class described comprising a bristle brush of general horse-shoe shaped configuration in top plan view, a twisted wire core embedded centrally in said brush, the ends of the wire as well as the ends of the brush being spaced apart to permit the diameter of the brush to be varied to fit the work, said wire-ends being bent laterally and then offset inwardly to occupy a position substantially over the center of the brush, at which point the wire-ends have their terminals bent upwardly at substantially right angles to the inwardly offset portions and brought together in parallel relation to provide a shank, and a handgrip attached to said shank.
2. An artificial denture brush of the class described comprising a bristle brush of general horse-shoe shaped configuration in top plan view, a twisted wire core embedded centrally in said brush, the ends of the wire as well as the ends of the brush being spaced apart to permit the diameter of the brush to be varied to fit the work, said wire-ends being bent laterally and then offset inwardly to occupy a position substantially over the center of the brush, at which point the wire-ends have their terminals bent upwardly at substantially right angles to the inwardly offset portions and brought together in parallel relation to provide a shank, and a handgrip attached to said shank, said handgrip being in the form of a spherical knob.
3. As a new article of manufacture, an artificial denture brush comprising an approximately horse-shoe shaped bristle brush having its ends spaced apart for adjustment toward and from each other, a twisted wire core centrally embedded in said brush and having its opposite end portions exposed through the ends of said brush and brought together in converging relationship, said end portions being offset laterally and then turned to overlie the center of the brush where the extremities thereof are bent at right angles to the brush and core and brought together in parallel relation to form a handle attaching shank, a spherical knob constituting a handle and having a central socket in which said shank is fastened.

In testimony whereof I affix my signature.

ALFRED E. SWANSON.
